UNITED STATES PATENT OFFICE.

ERICK A. HAHN, OF CHICAGO, ILLINOIS.

FLY-PAPER APPLIANCE.

Application filed March 16, 1923. Serial No. 625,610.

This invention relates to improvements in fly paper appliances and has for its object to provide a new and improved appliance of this description. The ordinary fly paper is difficult to handle. It is placed on tables and elevated places and is liable to have things laid upon it or be blown on the floor and stepped on or turned upside down and has many other objectionable features. One of the objects of the present invention is to provide a fly paper appliance by means of which these objections are obviated and which can be easily stored and handled. Another object of the invention is to provide a fly paper appliance which will be attractive and which can be used also as an advertising device. The invention has other objects which are more particularly pointed out in the following description.

Referring now to the drawings:

Fig. 1 is a perspective view showing the appliance assembled in operative position.

Fig. 2 is a view of the upper end of the device shown in Fig. 1 with the advertisement attached to the top thereof.

Fig. 3 is a view of the fly paper section flattened out.

Fig. 4 is a sectional view taken on line 4-4 of Fig. 1.

Fig. 5 is a top view of the base of the appliance before the holding pieces are moved up to the position shown in Fig. 1.

Fig. 6 is a sectional view taken on line 6-6 of Fig. 1.

Like numerals refer to like parts throughout the several figures.

Referring now to the accompanying drawings herein, I have shown one form of the invention. I form the fly paper 1 into a sheet of such shape that it can be formed into a hollow upright section or body 2 preferably larger at the base than at the top. I prefer to provide stiffening pieces 3 having a portion 4 of the fly paper project beyond these stiffening pieces. I also provide stiffening pieces 5 at the bottom and stiffening pieces 6 at the top. Each side stiffening piece 3 may be enlarged as at 6' at the top to form one of the top stiffening pieces.

These side stiffening pieces may also be arranged so that the bottom stiffening pieces 5 next to them will be integral with them. It is of course evident that any arrangement of these stiffening pieces may be made. The stiffening pieces at the top and bottom are arranged so that the fly paper can be easily

bent to be set up into position or easily folded for storage or shipment. When it is desired to fold it for storage or shipment it may be folded along the dotted lines 7 Fig. 60 3. Some suitable support or base is provided for holding the fly paper section in an upright position. Any suitable arrangement for this purpose may be used. As herein shown I have illustrated a cheap and convenient base 8 of comparatively stiff material such as cardboard or the like. This base piece is formed so as to have the upwardly projecting holding parts 9, see Fig. 1. These holding parts may be arranged in any desired manner. I prefer, however, to form them out of the base itself by simply cutting the material at the lines 10, Fig. 5, and then when it is desired to set the device up, push up the parts 9 to the position shown in Figs. 75 1 and 6.

In the use of the device the fly paper section is made up and is provided on one face with any of the usual glues which attract flies, one such glue, for example, consisting of rosin, linseed oil and honey. This glue will be applied when in warm condition to the face of the paper which is to be exposed. This will be the lower face in Fig. 3 and is the outer face in Fig. 1. The paper is then 85 folded with the sticky face inside. This forms a flat sheet, as it were, and the base 8 is also flat and these parts can thus be stored in a small space or easily shipped to the point desired, being sent by mail or in any 90 other way. When it is desired to use the fly paper, the folding parts 9 of the base 8 are moved upwardly and the fly paper is opened out and then folded to the position shown in Fig. 1 and inserted in between the 95 holding pieces 9. These holding pieces are then moved against the face of the fly paper and the fly paper will adhere thereto and thus be held in proper position. I may also fold over one of the edges 4 and cause it to 100 adhere to the adjacent pieces of fly paper and this will hold the fly paper in proper position. Either or both of these means may be utilized for this purpose. I may provide at the top a piece 11 by means of which the 105 device may be hung up in any desired place. As shown in Fig. 3 the piece 11 is integral with the stiffening piece 3. I may also provide an advertising section 12, see Fig. 2, 110 upon which any suitable advertising matter may be placed and this section may be used either when the device is hung up or when it

is set up on its base. It will thus be seen that by means of this device the fly paper may be stored in small spaces and easily shipped in a folded collapsible condition and may be 5 then easily and quickly set up so as to be in an upright position and therefore be out of the way and when in an upright position it may be set upon counters, tables, windows or other places or may be hung up at any point desired. When in any of these positions articles will not be laid upon it or hands or elbows placed upon it. I have further found that when the fly paper is in an upright position it is more effective in catching the 10 flies for when in a flat position the flies can fly over it but when in an upright position they light upon it. I may also provide the base 8 with any suitable advertising matter. This appliance can be easily and cheaply 15 made and is very convenient and effective for the purposes set out.

I have described in detail a particular construction embodying the invention but it is of course evident that the parts may be 20 varied in many particulars without departing from the spirit of my invention and I

therefore do not limit myself to the particular construction shown.

When the base 8 is made of heavy cardboard I may cut the paper partially through 30 along the dotted lines in forming the pieces 9 so that these pieces can be easily pushed up the remaining portion of the unsevered pasteboard forming hinges, as it were, to hold the pieces 9 on the base and yet permit 35 them to be moved up.

I claim:

A fly paper appliance comprising a piece of paper having adhesive thereon, stiffening devices at the edges and the bottom 40 of said paper arranged so that when the paper is formed into a hollow upright device the stiffening devices will hold it in shape, a portion of the paper with the adhesive thereon projecting beyond said stiffening devices, a base upon which said paper rests, and confining devices for confining the paper to a predetermined portion of said base. 45

Signed at Chicago county of Cook and 50 State of Illinois, this 8th day of March 1923.

ERICK A. HAHN.
